ATTORNEY

UNITED STATES PATENT OFFICE

DAVID BLAIR, OF CHICAGO, ILLINOIS

GARMENT

Application filed May 24, 1930. Serial No. 455,440.

The invention relates to a separable garment such as a combined corset and brassière and its object is to provide novel means by which the upper part of a garment as a brassière is removably attached to the lower part or corset and is positively positioned thereon and prevented from gapping or riding when the wearer is stooping or her body is in active motion in recreational endeavor or in sports.

10 The invention consists in a member carried by the lower part of a garment and adapted to receive a section of the upper part that is attachable to the lower part.

15 The invention is illustrated in the accompanying drawings in which

Figure 1 is a rear elevational view of the assembled corset and brassière and Fig. 2 an enlarged view of a fraction of the same partly detached.

20 In the illustrative embodiment of the invention 1 represents a corset and 2 a brassière. A loop 3 is secured to the central upper rear portion of the corset. The brassière is formed in the body encircling section 4 and 25 the rear sections 5 and 6 that are secured to one end of the section 4. The section 6 is extended through the loop 3 and carries an eye 7 at its free end which is adapted to be engaged by a hook 8 carried on the rear side 30 of the opposite end of the section 4. Similarly hooks 9 on the latter end of section 4 are engageable in eyes 10 carried at the free end of the section 5.

35 Suitable fasteners may be provided on the brassière that will engage cooperating members on the corset by which the brassière may be attached to the corset. I do not show the fasteners as they may be in any form and located at any convenient or desirable point.

40 The loop 3 preferably contains a short, suitably covered strip commonly known as "corset boning" so that the loop will remain flat and sufficiently rigid to hold the upper part 45 of the garment in position when the section 6 is engaged in the loop.

The upper part of the garment is readily removed from the lower part for cleansing and the form illustrated is but one of many to 50 which the invention is adaptable, such as

girdles, step-ins, bandeau sets, uplift garments, underwear and the like.

What I claim is:

1. In a garment the combination of an upper body encircling member, two sections 55 one above the other and extending from one end of the body encircling member, securing means at the free ends of both extending sections to cooperate with securing means on the opposite end of the body encircling member 60 for detachably securing the same together, a lower body encircling member and a loop secured to the upper portion of said lower member, the lower extension on the upper body encircling member being adapted 65 to be extended through the loop.

2. In a garment the combination of a brassière, two sections one above the other and extending from one end of the brassière, 70 cooperating members on the opposite end of the brassière and on the free ends of both extending sections for detachably securing the same together, a corset and a loop on the upper rear portion of the corset adapted to receive the lower extension section on the 75 brassière.

In witness whereof I have hereunto subscribed my name.

DAVID BLAIR.
